CARRIAGE CONTROL AT TABULATION
REBOUNDING

Harry C. Yaeger, West Hartford, Conn., assignor
to Underwood Corporation, New York, N. Y., a
corporation of Delaware

Application December 12, 1950, Serial No. 200,470

7 Claims. (Cl. 197—176)

1

This invention relates to typewriters and in particular to devices for controlling rebounding of the carriage at terminations of tabulations, so that the carriage will settle in the intended letter feed position.

Devices of this general nature are old and known in the art, but are either complicated or are apt to function unreliably, particularly if the letter feed pitch of the carriage is small. Furthermore, a great many machines sold are equipped with decimal tabulating mechanism, which further complicates the problem of providing simple and reliably effective control to assure settling of the carriage in the required letter feed position.

It is an object of the invention to provide for reliable carriage control at the end of each tabulation through efficient, simple and reliably exercised control over the escapement wheel.

It is another object of the invention to provide a rebound controlling device which is capable of controlling reliably and efficiently a letter feed carriage at the conclusions of tabulations even though the machine has a small letter feed pitch.

A still further object is to provide a reverse-rotation checking means for the escapement wheel and to control efficiently and reliably such means for activation during tabulations and for deactivation a definite time interval after escapement control is reestablished at the end of the tabulating runs, the escapement and the reverse-rotation checking means cooperating to assure that the carriage settles always in the intended letter feed position.

A still further object is to provide in association with the escapement teeth of the escapement wheel a reliably operative reverse-rotation checking means, which is cooperatively controlled in conjunction with the escapement to insure settling of the carriage in the proper letter feed position.

Other objects and advantages will be evident from the detailed description which follows.

Referring now to the drawings:

Figure 1 is a right hand sectional side elevation of a typewriter carriage and supporting structure, together with a letter feed escapement for the carriage and a power tabulating mechanism.

Figure 2 is a perspective view looking from the right rearward portion of the machine upwardly at an angle onto the letter feed escapement mechanism and associated rebound control mechanism, all parts being shown in their normally prevailing positions.

Figure 3 is a bottom elevation of the escapement mechanism, the rear portion of such mechanism facing toward the top of the sheet, and the escapement having been conditioned for tabulating travel of the carriage and the rebound checking device having been capacitated.

Figure 4 is a bottom view similar to Figure 3, 60 wheel 20 rotates in a direction opposite to the

2

but the parts are illustrated in positions which they assume at the instant of carriage rebounding, and finally,

Figure 5 is a bottom elevation similar to Figures 3 and 4, with the parts shown in their normal, restored positions, identical as in the perspective illustration of Figure 2.

Directing attention now particularly to Figure 1, a carriage 11 is adapted to travel in letter feed and return directions upon a trackway 12 which constitutes part of the framework of the machine, the carriage having a rail 13 which by means of anti-friction elements 14 is guided upon the trackway 12. Above the rail 13, the carriage 11 supports a usual platen roll 15 and at the rear a rack bar 16 has a series of usual key-settable tabulating stops 17 arranged at letter space intervals. A spring motor 18 supported on the framework of the machine by means of a strap connection urges the carriage 11 constantly leftwardly, that is, in letter feed direction. Opposite directional movements of the carriage are translated into opposite rotational movements of an escapement wheel 20. The latter is arranged on the lower end of a vertical shaft 21 which at the top has a pinion 22 in mesh with a carriage-supported rack 23. The wheel 20, the shaft 21 and the pinion 22 comprise an assembly rotatably mounted by an upper bracket 24 and a lower bracket 25.

Normally the carriage is held at rest against the urge of the spring motor 18 in that one of the teeth 28 on the escapement wheel 20, see Figures 2 and 5, abuts against the end of a holding dog 27. The dog 27 is carried pivotally at 29 on the underside of an escapement rocker 30 and the latter is rockably mounted on trunnions 31. Said rocker carries on the top side a usual stepping dog 32 which normally is fully above the teeth of the escapement wheel 20, and held advanced in respect to the holding dog 27 by means of a spring 33. The spring, by having an anchorage on a pin 34 of the dog 27, serves also to bias the latter to swing into the orbit of the wheel teeth 28.

Incidental to each typing operation the escapement rocker 30 is vibrated between limits in a usual manner, first to swing the dog 27 downwardly therewith clear of the active wheel tooth to free the carriage for letter feed stepping under power of the spring motor 18. This swings the stepping dog 32 temporarily into the path of the next wheel tooth, and when the escapement rocker 30 vibrates oppositely, the holding dog 27 will intercept the wheel 20 by the next tooth 28, the stepping dog 32 meanwhile assuming again a position clear of the escapement wheel. The pin 34 on the dog 27 is straddled by a notch provided in the rocker 30 for establishing pivotal limits for said dog. During carriage return the escapement

arrow indicated in Figure 2 and the teeth 28 of the escapement wheel crowd the dog 27 idly outwardly by camming action.

For convenience of illustration a power actuated tabulating mechanism corresponding to the patent to Helmond, No. 2,303,878, dated December 1, 1942, having a single counterstop element is shown, although the feature of the invention whereby the carriage will settle to the accurate intended letter feed position at the end of each tabulation has been devised particularly to operate also reliably in conjunction with decimal tabulators, such as the power tabulating mechanism disclosed in the patent to Yaeger, No. 2,386,060.

The shown tabulating mechanism comprises a normally retracted counterstop reed 37 underneath the tabulator rack 16 which is projectable from the position seen in Figure 1, upwardly into the range of a tabulator stop 17. At operation of a tabulator key 38, a transversely extending lever 39 in the machine receives downward motion to depress a lever 40 having a hook element 50 to descend on a lug of a power actuator 51. This engages a snatch pawl 53 with a constantly turning, toothed shaft member 52. Said actuator 51 at one end is borne pivotally on a pendant arm 54 and a spring 55 normally urges the same rearwardly and away from the toothed power member 52, to occupy the idle position seen in Figure 1. The actuator receives a power movement toward the front of the machine when the snatch pawl is brought into engagement with the toothed shaft 52. There ensues then an operation of a link 56 which rocks a structure 57, which in turn by means of a link 58 and a lever 60 imparts an upward movement to the reed 37 against the action of a return spring 61. The upper end of the reed 37 reaches through a perforation provided in a top plate 63 of a tabulator housing 64 and said perforation is wide enough in the direction of carriage travel to give said reed 37 some capacity for lateral movement to the right for a latch edge 65 on the right of the reed at projection of the latter to catch over a ledge provided by a plate 66. This latching action takes place under the tension of a spring, indicated at 67, which pulls the reed 37 rightwardly a fraction of a letter feed space. During the projection of the reed 37 the lever 60 operates a bell crank 68 carried pivotally at 70 upon an ear 69 of the bracket 25. During the first part of the projecting movement for the reed 37 a downreaching arm 71 of the bell crank 68 moves first idly from the position seen in Figure 5. After the upper end of the reed 37 has moved above the lower edge of the tabulator stop 17, said arm 71 will pick up and swing the holding dog 27 clear of the escapement wheel tooth which has to this moment been active. The spring motor 18 is thus enabled to pull the carriage in letter feed direction until a tabulator stop 17 engages and displaces the projected reed 37 leftwardly to the limit in the perforation. This places the latch edge 65 free of the plate 66 so that return spring 61 associated with the reed will retract the latter to normal position. During such retraction of the reed, the downreaching arm 71 of the lever 68 swings rearwardly and renders the holding dog 27 free for movement to effective position under the power of the spring 33, see Figures 2 and 5. The movement of the arm 71 in regard to controlling the dog 27 is such that the latter will move into advance ro-

tation blocking position with reference to the escapement wheel teeth 28 before the tabulator reed 37 moves fully below the tabulator stop 17. Thus, at the end of each tabulating run the dog 27 reliably assumes control over the carriage so that the latter cannot pass beyond the intended letter feed position. The sudden violent arrest of the carriage at the encounter of the tabulator stop 17 with the reed 37, especially after long tabulating runs, results in violent rebounding action of the carriage, and here the problem is to provide efficient means to cause the required tooth of the escapement wheel to settle against the holding dog 27 so as in turn to assure settling of the carriage in the proper letter feed position. In practical machines there are of necessity various points of looseness and opportunity for yield in the connecting structure between the escapement wheel 20 and the carriage supported stop 17, so that the escapement wheel 20 at violent tabulating arrests of the carriage will get temporarily out of step with the carriage. While the contributing factors which cause the escapement wheel 20 to get out of step with the carriage are present at various points, their aggregative presence is schematically indicated by showing play in the toothed engagement between the pinion 22 and the rack 23 in Figures 3 to 5, inclusive. The fact that the escapement wheel gets out of step with the carriage at tabulating arrest of the latter has been the source of great difficulty especially in fine letter feed pitch machines, in that rebounding controls applied to the carriage failed to reliably control the escapement wheel at the vital instant.

According to the invention reliable control of the escapement wheel is assured at the terminations of all tabulating runs, by provision of a device which during rebounding of the carriage controls the escapement wheel directly and with precision, specifically so that ultimately the proper escapement wheel tooth 28 will be caught by the escapement dog 27.

To the end stated, there is provided a reverse rotation blocking device in the form of a rotation checking pawl 76 pivotally carried by a screw 77 on the underside of the escapement bracket 25. The pawl 76 occupies normally the position seen in Figures 2 and 5, fully clear of the orbit of the teeth 28 of the escapement wheel. At each institution of a tabulating run the downreaching arm 71 of the bell crank 68, through the intermediary of a connection comprising an interponent rod 78, imparts a forward swinging motion to a lever 80 reaching in the showings of Figures 3 to 5, inclusive, leftwardly from a pivot point 81 on the bracket 25. Toward the end of the forward swinging motion of the lever 80 a pin 82 engages a rear face on a lever 84 to swing the latter to the position seen in Figure 3, the motion of the lever 80 being limited by an ear 83 engaging a portion of the bracket 25. The lever 84 is pivotally carried by a stud 85 on the underside of the bracket 25 and has an arm 86 which by means of a spring 87 is yieldingly connected with the reverse-rotation check pawl 76. Therefore, when the lever 84 is in the operated position as seen in Figure 3, the spring 87 urges the pawl 76 into reverse-rotation checking relation with the escapement wheel 20. During the movement of the levers 80 and 84 to their operated positions seen in Figure 3, a latch element 88 pivotally carried at 90 on the lever 80, facilitated by a spring 91 glides over an ear 92 on the lever 84 to arrive

finally in the position seen in Figure 3. Thus during tabulations and while the tabulator reed 37 remains projected, the lever 80 remains operated and therefore the check pawl 76 remains activated. Meanwhile, a nose on the latch element 88 rests under the tension of the spring 91 against a pin 93. The escapement wheel during the tabulation turns in the direction of the arrow indicated in Figure 3 and the escapement wheel teeth 28 advance and glide idly over a back face 95 on the check pawl 76. As the tabulator stop 17 meets the counterstop, one of the escapement wheel teeth 28 will have passed slightly beyond the check pawl 76 and the latter will spring-move into rebound checking position behind such tooth. When the tabulator stop 17 clashes against the counterstop reed 37, as before stated, the latter restores responsively under the power of the spring 61, and substantially concomitantly the carriage 11 rebounds. The escapement wheel 20 rebounds also, but delayedly due to the stated capacity for out-of-step movement. The rebound check pawl 76 meanwhile stands ready in position behind the appropriate escapement wheel tooth 28 to stop reverse rotation of the escapement wheel 20 as shown in Figure 4, said check pawl 76 being backed up by a motion limiting pin 96. During an initial portion of the return movement of the counterstop reed 37, the escapement wheel dog 27 moves to the escapement wheel controlling position seen in Figure 4. In such movement the escapement wheel dog 20 arrives in the position seen in Figure 4 before the reed 37 moves out of engagement with the tabulator stop 17. Meanwhile, as seen in Figure 4, the back check pawl 76 is held active by the latch 88 in cooperation with the ear 92, even though the pin 82 leaves the before stated face on the lever 84.

After the parts assume the position seen in Figure 4 the reed 37 continues its retracting movement and the lever arm 71 leaves the escapement dog as in Figure 5. During the very last increment of retracting movement of the reed 37 the pawl 88 rides off the edge of the ear 92, wherefore the reverse-rotation check pawl 76 stays active sufficiently late beyond the instant of rebounding action of the carriage transmitted to the escapement wheel. As the lever 80 nears the fully normal position seen in Figure 5, the latch 88 rides clear of the ear 92 and the spring 91 returns the lever 84 to the normal position seen in Figures 2 and 5, wherein the lever 84 abuts a collar on the pawl 76 and wherein the pawl is forced to idle position by the end of the arm 86 engaging the pawl 76. Meanwhile the carriage 11 under the power of the spring motor 18 settles in advance direction in the exact desired letter feed position, inasmuch as the escapement dog 27 will intercept the proper one of the wheel teeth 28.

Additionally to the rod 78, the connection between the arm 71 and the lever 80 comprises extending therebetween a spring 97 having the said rod 78 accommodated in the turns thereof. The spring 97 is very strong and always confines rod 78 snugly between the arm 71 and an adjustable screw 100 on the lever 80. The effect is that the rod 78, the spring 97 and the screw 100 constitute together an adjustable connection between the arm 71 and the lever 80, it being understood that the screw 100 is so adjusted that the latch 88 will move clear of the ear 92 at the last possible moment of the restoring movement of the arm 71, thereby to keep the check pawl 76 sufficiently long capacitated to perform its intended function.

The end of the lever 80 which carries the pawl

88 is guided horizontally in that the portion which carries the pawl 88 underlies the bracket 25 and in that the lever 80 has a tongue 90 overlying the bracket 25.

5 Due to the stated opportunity for out-of-step movement of the escapement wheel 20 with reference to the carriage, only part of the rebound motion of the latter is transmitted to the escapement wheel, wherefore the back check pawl 76 is contacted at a later time and less violently as would be the case otherwise. Actually, due to the stated capacity for out-of-step movement, the carriage is allowed to rebound in excess of a letter feed space, while the escapement wheel 20 in its reverse rotation is restricted to somewhat less than a tooth space. In fine pitch machines this difference of rebound motion of the carriage with respect to the escapement wheel is very pronounced, and has been the source of great difficulty in providing for accurate, efficient carriage control at terminations of tabulating runs. The structure of the invention on the other hand provides for simple, reliable carriage control even if the letter feed pitch of the machine is small. 20 25 30

It is understood that at the end of each tabulation the escapement dog 27 in conjunction with the back check pawl 76 is in perfect control over the escapement wheel 20 to cause the carriage to settle with the escapement dog 27 intercepting the appropriate tooth 28 of the escapement wheel.

Having explained the nature and object of the invention and having specifically described a preferred embodiment thereof, what is claimed is:

35 1. In a machine of the class described, having a carriage urged in letter feed direction and an escapement wheel operatively connected with the carriage for advance and reverse movements by the latter, the combination with an escapement means cooperative normally with said escapement wheel for letter feed control, and tabulating means for the carriage comprising tabulating control means, normally inoperatively conditioned tabulating stop means, and means responsive to said control means to operatively condition said tabulating stop means and release said escapement wheel from control of said escapement means, and responsive to tabulating arrest of the carriage by said stop means to restore first said escapement wheel to the control of said escapement means and then to condition inoperatively said tabulating stop means, of normally incapacitated reverse-rotation checking means for said escapement wheel, and means to render said reverse-rotation checking means capacitated incident to the response of said responsive means to said control means, and to render it automatically incapacitated under control of the responsive means after said tabulating stop means becomes inoperatively conditioned.

responsive to the stopping of the carriage by said stop means to restore first said escapement wheel to the control of said escapement and then to inoperatively condition the said stop means, of a reverse-rotation checking means for said escapement wheel, normally held incapacitated by said responsive operated and restored means, and means to capacitate and to incapacitate said checking means by said responsive means respectively at operation thereof and pending a completion of its restoring movement beyond a position to inoperatively condition said stop means.

3. The combination with a machine having a frame and a carriage, and having means including an escapement wheel rotatable in an advance direction and in a reverse direction respectively by movement of the carriage in an advance direction and by movement of the carriage in a reverse direction, of means urging normally said carriage and said rotatable means in their advance directions, escapement means in control of said escapement wheel and operable to permit stepwise advance rotation thereof, said escapement means including a dog normally in position for holding the escapement wheel against advance rotation, a tabulator stop on the carriage, a counterstop on the frame normally out of cooperative range of said tabulator stop, a normally incapacitated device for blocking reverse rotation of said rotatable means, means to move said counterstop into cooperative range with said tabulator stop and additionally to release said dog and render said blocking device capacitated, and means automatically operated responsive to the engagement of said tabulator stop with the counterstop to move said dog to its effective position, and also to withdraw said counterstop and thereafter to incapacitate said blocking device.

4. In a machine of the class described having a frame, a carriage, means including an escapement wheel rotatable in an advance direction and in a reverse direction respectively by movement of the carriage in advance and in reverse directions, means urging normally said carriage and said wheel in their advance directions, and escapement means normally in control of said escapement wheel, operable to permit stepwise advance rotation thereof and including a normally effective dog holding the escapement wheel against advance rotation only; the combination with tabulating means having control devices, effective at the outset of any tabulation to place said holding dog free of said wheel and effective at each conclusion of a tabulation to render said holding dog again cooperative with said wheel, of means to control the escapement wheel at each conclusion of a tabulation while the carriage rebounds, comprising a normally retracted pawl for checking reverse rotation of said rotatable means, and means enabling said control devices to place said pawl under bias to move to a reverse-rotation checking position at the outset of any tabulation and to retract such pawl a short time interval after the holding dog has returned into cooperative relation with said wheel.

5. In a machine of the class described, having a carriage urged in letter feed direction and an escapement wheel operatively connected with the carriage for advance and reverse movements by the latter, the combination with an escapement means cooperative normally with said escapement wheel for letter feed control, and

tabulating means for the carriage comprising tabulating control means, normally inoperatively conditioned tabulating stop means, and means responsive to said control means to operatively condition said tabulating stop means and release said escapement wheel from control of said escapement means, and responsive to tabulating arrest of the carriage by said stop means to restore first said escapement wheel to the control of said escapement means and then to condition inoperatively said tabulating stop means, of a reverse-rotation checking pawl for said escapement wheel normally clear thereof, and means to urge said checking pawl into cooperative relation with the teeth of the escapement wheel incident to the response of said responsive means to said control means, and means to keep said urging means active until an instant after said tabulating stop means becomes inoperatively conditioned.

6. In a machine of the class described, having a carriage urged in letter feed direction and an escapement wheel operatively connected with the carriage for reverse movements by the latter, the combination with an escapement cooperative normally with said escapement wheel for letter feed control, and tabulating means for the carriage comprising carriage intercepting means, and means responsive to functioning of said intercepting means to place the escapement wheel under control of said escapement, of normally incapacitated means for checking reverse rotation of said escapement wheel incident to rebounding of the carriage at interception thereof, including spring-restored means automatically operated to capacitate said reverse-rotation checking means, means to latch said spring-restored means automatically in operated position, and means to release said latch means automatically

a short time interval after the escapement wheel is restored to the control of said escapement.

7. In a machine of the class described, having a carriage urged in letter feed direction and an escapement wheel operatively connected with the carriage for reverse movements by the latter, the combination with an escapement cooperative normally with said escapement wheel for letter feed control, and tabulating means for the carriage comprising carriage intercepting means, and means responsive to functioning of said intercepting means to place the escapement wheel under control of said escapement, of normally incapacitated means for checking reverse rotation of said escapement wheel incident to rebounding of the carriage at interception thereof, including a reverse-rotation checking means normally clear of the teeth of the escapement wheel, means movable to an operated position to spring-urge said checking means for reverse-rotation checking action on the teeth of the escapement wheel, means to latch said movable means in operated position, and means controlled by said responsive means to release said latch means automatically a short time interval after it has placed the escapement wheel under the control of the escapement.

HARRY C. YAEGER.
